(57) **CLAIM**

The ornamental design for a battery pack, as shown and described.

DESCRIPTION

FIG. 1 is a front view of the battery pack according to the present invention.

FIG. 2 is a rear view of the battery pack of FIG. 1 according to the present invention.

FIG. 3 is a top view of the battery pack of FIG. 1 according to the present invention.

FIG. 4 is a bottom view of the battery pack of FIG. 1 according to the present invention.

FIG. 5 is a left side view of the battery pack of FIG. 1 according to the present invention.

FIG. 6 is a right side view of the battery pack of FIG. 1 according to the present invention.

FIG. 7 is a front perspective view of the battery pack of FIG. 1 according to the present invention; and,

FIG. 8 is a front perspective view of an alternative embodiment of the present invention identical to the embodiment of FIG. 1 having a portion of increased thickness.
